UNITED STATES PATENT OFFICE.

FRIEDRICH WILHELM JOLITZ, OF WEST DULUTH, MINNESOTA.

INSTEP-PROTECTOR.

No. 881,079.

Specification of Letters Patent. Patented March 3, 1908.

Application filed November 1, 1906. Serial No. 341,618.

to all whom it may concern: .

Be it known that I, FRIEDRICH WILHELM JOLITZ, a citizen of the United States, residing at West Duluth, in the county of St. Louis and State of Minnesota, have invented 5 a new and useful Instep-Protector, of which the following is a specification.

This invention relates to an instep protector of that type designed for use on the 10 under side of the shank of a shoe or boot to reinforce the shank and to receive the wear from a shovel or spade during digging, spading, tamping ties, and similar operations, and also to protect the instep of the foot from 15 becoming sore.

The invention has for one of its objects to provide a device of this character which is of 20 simple and inexpensive construction, capable of being readily and firmly secured to the shoe, and which possesses increased usefulness.

A further object of the invention is to provide the device with means which coöperates with suitable fastenings, such as screws, 25 nails, and the like, for firmly holding the device on a boot or shoe.

With these objects in view, and others, as will appear as the nature of the invention is better understood, the invention comprises 30 the various novel features of construction and arrangement of parts, which will be more fully described hereinafter and set forth with particularity in the claims appended hereto.

In the accompanying drawing, which illustrates one of the embodiments of the invention, Figure 1 is a partial perspective view of a shoe, inverted, showing the instep protector applied thereto. Fig. 2 is a partial 35 side elevation of a shoe, partly broken away at the instep protector and showing the latter in longitudinal section. Fig. 3 is a perspective view of the blank from which the protector is made. Fig. 4 is a transverse 40 section of the protector.

Corresponding parts in the several figures are indicated throughout by similar characters of reference.

Referring to the drawing, 1 designates the 45 sole of a shoe, 2 the shank of the sole, and 3 the heel. On the bottom surface of the shank 2, the instep protector 4 is arranged.

The protector or device 4 is made of any suitable material, such, for instance, as sheet

metal of suitable gage to provide ample stiffness and to stand the wear for a considerable length of time.

The protector is made from a blank stamped out of sheet material, or otherwise suitably formed, and is of the general shape 60 of a heraldic shield. As shown in Fig. 3, this blank 5 is provided with a pair of sharp members or spurs 6 at one end which project in the general direction of the length of the plate or blank 5. These spurs are spaced 65 apart and are flush with the curved edges 7 of the plate 5, and between the spurs is formed a tongue 8 having a central aperture 9. At the pointed end of the plate opposite from the spurs is an aperture 10, the said 70 aperture, in connection with the aperture 9, being adapted to receive screws or other fastening devices whereby the completed article is attached to the shoe. After the blank is formed, the tongue 8 is turned out 75 laterally from between the spur 6 into a plane at right angles to the body of the plate 5, so as to form a lug which is intended to bear against the front vertical surface of the heel 3. During the next operation, the plate 5 is 80 pressed, so that on its upper face, that is, the face presented to the shank 2 of the shoe, it will be convex in longitudinal dimension, as shown at 11, Fig. 2, and concaved in transverse dimension, as shown at 12, Fig. 4, 85 thereby closely conforming to the compound curvature of the shank 3 of the shoe. The next step in the process of forming the protector is the forming of a plurality of transverse depending ribs or corrugations 13. 90 These corrugations serve primarily as means for engaging the top edge of the blade of the spade or shovel, and they are suitably spaced apart, so that the said edge can be held between any two of the corrugations, and they 95 serve secondarily to stiffen the plate 5. Obviously, the protector can be made by casting, if desired, and the construction will be substantially the same as that of the article just described, that is to say, it will 100 include the plate 5, spurs 6, the apertured lug 8, the transverse corrugations or ribs 13, and the aperture 10. If desired, the ribs 13 can be omitted.

In applying the protector to a shoe, the 105 plate 5 is presented to the shank of the shoe with the corrugations 13 on the outside, and the longitudinal center line of the plate will

coincide with the center line of the shank. The spurs 6 are presented to the front surface 14 of the heel at the root thereof, and these spurs are driven into the heel by striking 5 with a hammer upon the stud 8 or any other convenient part of the device. The spurs are driven in to such a distance that the stud 8 will abut the front 14 of the heel. A screw, nail, or other suitable fastening, 15, which is 10 driven into the heel through the aperture 9 of the lug 8, operates, in connection with the spur 6, to firmly hold the heel end of the protector in position. The front end of the plate is secured to the shank of the shoe by any 15 suitable fastening, such as a screw 16, as shown in Fig. 1, or a clench nail or rivet 17, as shown in Fig. 2.

From the foregoing description, taken in connection with the accompanying drawing, 20 the advantages of the construction will be readily appreciated by those skilled in the art to which the invention appertains. The plate of the device is of substantial construction so as to stiffen the shank of the shoe and 25 prevent it from breaking and thus add greatly to the life of the shoe and also prevent the instep of the foot from being injured. The wear from contact with the upper edge 30 of the blade of the spade or shovel takes place on the flat portions 18, and the transverse ridges or corrugations 13 serve to prevent the shovel or spade from turning by its coming in contact with stones, roots, and other objects, as the blade is penetrated into 35 the earth.

I have described the principle of operation of the invention, together with the apparatus which I now consider to be the best embodiment thereof, but I desire to have it 40 understood that the apparatus shown is merely illustrative, and that various changes may be made, when desired, as are within the scope of the invention.

What is claimed is:—

1. An instep protector comprising a plate 45 having at one end an outturned apertured lug and a plurality of outstanding transversely-extending ribs spaced on the plate and from the lug, the portions of the plate between the adjacent ribs and between the 50 lug and rib adjacent thereto being comparatively flat.

2. An instep protector comprising a plate apertured at one end, a pair of spurs at the other end of the plate, an apertured lug on 55 the plate adjacent to and between the spurs and extending at right angles to the plate, and a plurality of spaced transversely extending ribs projecting from the plate.

3. An instep protector comprising a plate 60 of sheet metal wider at its rear than at its front end and provided at the rear end with a central outturned flange and a rearwardly-projecting stud on each side of the flange in the plane of the plate, a perforation being 65 provided in the flange and plate for securing the protector to the heel and sole of the shoe, and a plurality of parallel ribs on the plate between its front end and the flange.

4. As an article of manufacture, an instep 70 protector consisting of a plate of sheet metal provided near each end with an orifice and on one face with a plurality of spaced transverse ribs and having its rear end broader than its front end, the rear end being formed with a 75 broad, short central lug disposed transversely at right angles to the ribbed face of the plate and with a sharp spur on each side of the lug.

In testimony that I claim the foregoing as my own, I have hereto affixed my signature 80 in the presence of two witnesses.

FRIEDRICH WILHELM JOLITZ.
